STARTER GEARING FOR INTERNAL
COMBUSTION ENGINES

Thomas B. Martin, Dayton, Ohio, assignor to Bendix Aviation Corporation, South Bend, Ind., a corporation of Delaware

Application March 4, 1941, Serial No. 381,688

13 Claims. (Cl. 74—6)

The present invention relates to starter gearing for internal combustion engines and more particularly to that type in which a motor-driven pinion is shifted manually or by other extraneous means into and out of engagement with a member of an engine to be started.

In installations of this character it is desirable to connect the pinion to the starting motor through some form of overrunning clutch device in order to permit the engine member to accelerate when the engine becomes self-operative without accelerating the armature of the starting motor to a dangerous or harmful speed of rotation. Considerable difficulty has been encountered in constructing an overrunning clutch for this purpose which will on the one hand transmit the cranking torque at all times without slippage, and on the other hand will release and overrun without sticking.

It is an object of the present invention to provide a novel starter gear shift which is efficient and reliable in operation and simple and economical in construction.

It is another object to provide such a device which is arranged to couple the pinion to its drive shaft positively and with small lost motion upon the actuation of said shaft.

It is a further object to provide such a device in which the coupling action may be cushioned if deemed desirable without rendering the action any less positive and certain.

It is another object to provide such a device in which the coupling is arranged to overrun freely when the engine becomes self-operative without causing undue acceleration of the drive shaft.

It is another object to provide such a device in which localized stresses are avoided, and the torque is transmitted by pressures on comparatively large surfaces which are arranged at a considerable angle to the direction of the force transmitted.

Further objects and advantages will be apparent from the following description taken in connection with the accompanying drawings in which:

Fig. 1 is a side elevation partly in section of a preferred embodiment of the invention;

Fig. 2 is a section taken substantially on the line 2—2 of Fig. 1;

Fig. 3 is a section taken substantially on the line 3—3 of Fig. 1;

Fig. 4 is a view similar to Fig. 1 showing a second embodiment of the invention;

Fig. 5 is a section taken substantially on the line 5—5 of Fig. 4;

Fig. 6 is a view similar to Fig. 1 of a third embodiment of the invention;

Fig. 7 is a section taken substantially on the line 7—7 of Fig. 6;

Fig. 8 is a view similar to Fig. 6 showing the parts in operative or driving position;

Fig. 9 is a view similar to Fig. 4 showing the control nut fixedly attached to the drive sleeve instead of being frictionally clutched thereto, and showing the pinion bushing formed to act as a detent for the screw shaft;

Fig. 10 is a section taken substantially on the line 10—10 of Fig. 9; and

Fig. 11 is a detail in side elevation of the pinion with its clutch member and frictional mounting for the screw shaft illustrated in Fig. 9.

In Fig. 1 of the drawings there is illustrated a power shaft 1 having a drive sleeve 2 splined thereon. A pinion member 3 is slidably journaled on the power shaft and connected for longitudinal movement with the drive sleeve by means of a barrel member 4 fixedly attached to the pinion as indicated at 5 and swiveled to the end of the sleeve 2 by means of a radial flange 6 on the end of the sleeve which is confined between split thrust rings 7 and 8 mounted in the interior of the barrel.

An overrunning torque transmitting connection between the sleeve and pinion is provided comprising a screw shaft 9 slidably journaled on the power shaft inside the barrel 4 and having clutch teeth 11 on one end thereof. A toothed clutch member 12 is rigidly mounted in the end of the sleeve 2 in any suitable manner as by welding or brazing in position to be engaged by the clutch teeth 11 of the screw shaft 9 when the screw shaft moves to the right in Fig. 1. A nut 13 is threaded on the screw shaft 9 within the barrel 4 and is maintained in frictional engagement with a washer 14 at the inner end of the barrel by spring means such as a dished spring washer 15 engaging an annular projection 16 on the nut and seated against the split thrust ring 7 in the barrel.

Means for shifting the sleeve 2 with the pinion and barrel longitudinally on the power shaft 1 to move the pinion into and out of engagement with an engine member, is provided in the form of a shift collar 17 slidably mounted on the periphery of the sleeve 2 and yieldably held against a split thrust ring 18 by a compression spring 19 bearing against the flange 6 of the sleeve.

Means for frictionally connecting the screw shaft 9 to the power shaft 1 is provided in the form of a spring clutch ring 21 (Fig. 3) anchored to the screw shaft at one end as by means of an outturned terminal portion 22 located in a radial bore 23 in the screw shaft, and wound around the power shaft in a direction to cause the clutch ring to grip the shaft when the shaft rotates in a forward direction as indicated by the arrow in Fig. 3.

In the operation of this embodiment of the invention, after the pinion 3 has been moved into engagement with an engine gear, rotation of the power shaft 1 by a starting motor, not illustrated, will cause rotation of the sleeve 2 by virtue of

its splined connection therewith and will also cause rotation of the screw shaft 9 by means of the clutch ring 21. Since the nut 13 is held stationary by its frictional connection through the washer 14 and the spring washer 15 with the pinion barrel 4, the screw shaft 9 will be caused to move to the right in Fig. 1 until the clutch 11, 12 is closed. Thereafter, the screw shaft is positively rotated through said clutch from the power shaft 1, and the nut 13 is forced against the washer 14 by the screw jack action between the screw shaft and nut whereby the pinion 3 is constrained to turn with the sleeve 2 and consequently with the power shaft 1. When the engine starts the overrunning of the pinion causes the screw shaft to be threaded to the left in Fig. 1, causing it to be declutched from the sleeve and power shaft whereby the pinion, barrel, nut and screw shaft overrun freely until the assembly is returned to idle position by the operator.

In the embodiment of the invention illustrated in Figs. 4 and 5 a power shaft 31 has splined thereon a sleeve 32, and a pinion 33 is slidably journaled on a bushing 34 freely mounted on the power shaft and extending into the end of the sleeve 32.

Sleeve 32 is provided with an enlarged bell 35 fixed to the sleeve in any suitable way as by welding or brazing as indicated at 36 and having a swiveled connection with the pinion 33 as by means of a flange 37 fixed in any suitable way to the pinion and confined in the end of the bell by means of a washer 38 located by a split lock ring 39.

The inner end of the pinion 33 is formed as a dental clutch 41, and a screw shaft 42 is slidably journaled on the bushing 34 and provided with clutch teeth 43 adapted to cooperate with the clutch 41. Means for yieldingly urging the screw shaft in a direction to close the clutch is provided in the form of a return spring 44 bearing against the screw shaft at one end and at its other end against a washer 45 retained by a flange 46 on the end of the bushing 34.

A nut 47 is threaded on the screw shaft 42 and is provided with a conical periphery 48 bearing against an inner conical surface 49 of the bell 35 so as to form a friction clutch connection therewith. Means for yieldingly holding these surfaces in contact is provided in the form of a spring washer 51 bearing against an annular projection 52 on the nut 47 and seated against a split thrust ring 53 in the bell 35.

Means for shifting the sleeve 32 along the power shaft 1 in order to cause the pinion 33 to engage an engine member, is provided in the form of a collar 54 slidably mounted on the sleeve 32 and maintained thereon by a split thrust ring 55 against the pressure of a spring 56 bearing against the end of the bell 35.

When the shift collar 54 is actuated by any conventional type of shift fork to move the pinion into operative position, power shaft 31 will be rotated by a starting motor, which rotation is thereupon transmitted through the splines to the sleeve 32 and bell 35, thus causing rotation of the nut 47 through its frictional connection with the bell 35. The screw jack action between the nut and screw shaft thereupon causes the screw shaft to move to the left, closing clutch 41, 43, after which the nut 47 is forced against the interior of the bell 35 so as to form a driving connection from the bell through the nut and screw shaft to the pinion. When the engine starts, the overrunning of the pinion causes the screw shaft

to declutch, thus permitting the pinion, screw shaft and nut to overrun until the sleeve and pinion assembly is moved back to idle position.

In Figs. 6, 7 and 8 a power shaft 61 has splined thereon a sleeve 62, and a pinion 63 slidably journaled on the power shaft has a nut 64 fixed thereto in any suitable way as indicated at 65. A bell 66 is suitably fixed on the end of the sleeve 62 surrounding the nut 64 and has a ring 67 of elastically deformable material mounted therein. Ring 67 is held under initial compression by means of a thimble 68 surrounding the nut 64 and seated against a shoulder 69 in bell 66, and a thrust ring 71 bearing against a split lock ring 72 in the open end of the bell. Nut 64 is provided with a radial flange 73 in the bell 66 adjacent the thimble 68 whereby the nut and consequently the pinion are swiveled to the bell and sleeve 62.

A screw shaft 74 is slidably journaled on the power shaft and is provided at one end with a clutch formation 75 adapted to engage a clutch member 76 fixed in the end of sleeve 62. Self-tightening means frictionally connecting the screw shaft to the power shaft 61 is provided in the form of a clutch ring 77 (Fig. 7) anchored to the screw shaft by an outturned end 78 lodged in a radial bore 79 of the screw shaft and wound around the power shaft in a direction to frictionally grip it when it turns in a forward direction as indicated by the arrow.

A shifting thimble 81 is slidably mounted on the sleeve 62, retained thereon by a split lock ring 82 and having a yielding thrust connection with the sleeve through a compression spring 83.

When the shift collar 84 is actuated by any conventional form of shifting fork to move the pinion into engagement with an engine gear such as indicated at 84 in Fig. 8, rotation of the power shaft 61 is transmitted to the sleeve 62 through its splined connection therewith and is transmitted to the screw shaft 74 by the friction clutch ring 77. Since the nut 64 is held stationary by its connection with the pinion 63, the screw shaft 74 is caused to move to the right, closing clutch 75, 76. Thereafter the nut 64 is caused to move to the left, compressing the elastic ring 67 until sufficient torque is built up to cause rotation to be transmitted to the pinion and engine gear.

When the engine starts, the overrunning of the pinion 63 causes the screw shaft 74 to declutch, whereupon the pinion, nut and screw shaft overrun until the pinion is moved back to idle position by the shifting means.

The structure illustrated in Figs. 9, 10 and 11 is similar to that shown in Figs. 4 and 5 and the parts are similarly numbered, but in this case the nut and bell are formed integrally and designated by the numeral 50, the pinion flange 60 is formed as the clutch member and is numbered 40, and the screw shaft 42 is frictionally connected to the pinion by cutting a spiral groove 30 in the projecting end of the pinion bushing 34a whereby the bushing acts as a self-expanding clutch within the screw shaft. The operation of this structure is substantially the same as that illustrated in Figs. 4 and 5 except that the connection to the pinion is more positive, and the traversal of the screw shaft is facilitated by reason of the fact that the spirally cut end of the bushing 34a is longitudinally compressible so that while the bushing retards rotation of the screw shaft, it does not materially impede its longitudinal movement.

Although certain embodiments of the invention

have been shown and described in detail, it will be understood that other embodiments are possible and various changes may be made in the construction and arrangement of the parts without departing from the spirit of the invention as defined in the claims appended hereto.

What is claimed is:

1. In a starter gear, a power shaft, a sleeve member slidably but non-rotatably mounted thereon, a pinion member slidably journalled on the shaft and connected for longitudinal movement with the sleeve, and an overrunning torque transmitting connection between the sleeve member and pinion member including a threaded ring slidably and rotatably mounted on the power shaft having clutch teeth on one end, a nut threaded thereon having a torque transmitting connection with one of said members; and clutch teeth rigid with the other said member and adapted to cooperate with the clutch teeth of the ring and form a torque transmitting connection therebetween.

2. In a starter gear, a power shaft, a sleeve member slidably but non-rotatably mounted thereon, a pinion member slidably journalled on the shaft and connected for longitudinal movement with the sleeve, and an overrunning torque transmitting connection between the sleeve member and pinion member including a threaded ring slidably and rotatably mounted on the power shaft independent from said sleeve having clutch teeth on one end, a nut threaded thereon having a torque transmitting and thrust connection with one of said members, and a toothed clutch member rigid with the other said member and adapted to cooperate with the clutch teeth of the ring and form a torque transmitting connection therebetween when said teeth are forced into engagement by the screw jack action of the ring and nut.

3. In a starter gear, a power shaft, a sleeve member slidably but non-rotatably mounted thereon, a pinion member slidably journalled on the shaft and connected for longitudinal movement with the sleeve, and an overrunning torque transmitting connection between the sleeve member and pinion member including a threaded ring slidably and rotatably mounted on the power shaft, a nut threaded thereon having a torque transmitting connection with one of said members, a frictional connection between the ring and the other of said members, and a positive torque transmitting connection to the ring established by the screw jack action of the ring and nut.

4. Starter gearing as set forth in claim 1 in which means are provided for cushioning the establishment of the driving connection between the sleeve and pinion.

5. Starter gearing as set forth in claim 1 incorporating a self-tightening frictional connection between the sleeve and nut.

6. Starter gearing as set forth in claim 1 incorporating a block of elastically deformable material interposed between the sleeve and nut and arranged to be compressed by the action of the threaded ring and nut to yieldably connect the sleeve to the nut for rotation in unison.

7. In an engine starter gear, a power shaft, a pinion slidably journalled thereon, and means for connecting the pinion to rotate with the shaft including a sleeve non-rotatably mounted on the shaft, a nut fixed to the sleeve and swiveled to the pinion, a ring threaded in the nut and frictionally connected to the pinion, and a clutch

connection between the screw shaft and pinion established by screw jack action between the ring and nut.

8. In an engine starter, a power shaft, a pinion slidably journalled thereon, a sleeve splined to the shaft and having a swiveled connection with the pinion, means for shifting the sleeve along the shaft, a threaded ring rotatably and slidably mounted on the power shaft having a clutch member at one end, a nut threaded on the ring, and means including a member cooperating with the clutch member on the ring to transmit rotation through the ring and nut from the sleeve to the pinion.

9. In an engine starter, a power shaft, a pinion slidably journalled thereon, a sleeve splined to the shaft and having a swiveled connection with the pinion, means for shifting the sleeve along the shaft, a threaded ring rotatably and slidably mounted on the power shaft, a nut threaded on the ring having a torque-transmitting connection with the pinion, and means including a clutch closed by the screw jack action of the ring and nut for transmitting rotation from the sleeve to the pinion.

10. In an engine starter, a power shaft, a pinion slidably journalled thereon, a sleeve splined to the shaft and having a swiveled connection with the pinion, means for shifting the sleeve along the shaft, a threaded ring rotatably and slidably mounted on the power shaft having a clutch member formed on one end, a nut threaded on the ring having a torque transmitting connection with the pinion, and a clutch member rigid with the sleeve cooperating with the clutch member on the ring to transmit torque from the sleeve through the ring and nut to the pinion.

11. In an engine starter, a power shaft, a pinion slidably journalled thereon, a sleeve splined to the shaft and having a swiveled connection with the pinion, means for shifting the sleeve along the shaft, a threaded ring rotatably and slidably mounted on the power shaft having a clutch member formed on one end, a nut threaded on the ring having a torque transmitting connection with the sleeve, and a clutch member rigid with the pinion cooperating with the clutch member on the ring under the screw jack action of the ring and nut to transmit torque from the sleeve through the ring and nut to the pinion.

12. In an engine starter, a power shaft, a threaded ring slidably journalled on the power shaft and frictionally connected to rotate therewith, a sleeve splined to the power shaft, a pinion slidably journalled on the power shaft and swiveled to the sleeve, a barrel fixed to the pinion, a nut threaded on the ring within the barrel and frictionally connected to the barrel, and clutch means closed by the screw jack action of the ring and nut for transmitting torque through the ring and nut from the sleeve to the barrel.

13. Manually shiftable engine starter gearing including a power shaft, a pinion, a sleeve splined to the power shaft, and an overrunning connection between the sleeve and pinion including a threaded ring formed as a clutch member having a floating bearing on the power shaft, a nut threaded on the ring, means for moving the sleeve, nut and pinion along the shaft in unison to mesh the pinion with an engine member, and means including a clutch closed by longitudinal movement of the ring in the nut to transmit rotation from the sleeve to the pinion.
